UNITED STATES PATENT OFFICE.

EDWARD WESTON, OF NEWARK, NEW JERSEY.

DESIGN FOR A CASE FOR ELECTRICAL MEASURING INSTRUMENTS.

SPECIFICATION forming part of Design No. 28,394, dated March 22, 1898.

Application filed February 14, 1898. Serial No. 670,831. Term of patent 14 years.

To all whom it may concern:

Be it known that I, EDWARD WESTON, a subject of the Queen of Great Britain, residing at Newark, in the county of Essex and State of New Jersey, have invented and produced a new and original Design for a Case for Electrical Measuring Instruments, of which the following is a specification, reference being had to the accompanying drawings, forming part thereof.

Figure 1 is a plan view of a case for an electrical measuring instrument, showing my design. Fig. 2 is a side elevational view of the same as seen looking at Fig. 1 from the left-hand toward the right-hand side of the drawings.

As shown in the drawings, the leading or material feature of my design consists of a case having a cylindrical body part C and two diametrically oppositely-disposed extensions E and E', each of less depth than the cylindrical part and located at opposite ends thereof, as clearly shown in Fig. 2, the extension E being of substantially sector-like form,

having vertical faces M M and F F and a cylindrical face C', the faces F F being so located with relation to the body part C and the faces M M as to form reentrant curves, while the extension E' is of substantially rectangular form.

P represents a panel on the upper or top face of the casing.

L L represent lug-like extensions from the bottom thereof.

Having described my invention, what I claim as new, and desire to secure by Letters Patent of the United States, is—

The design for a case for an electrical measuring instrument as herein shown and described.

In testimony whereof I have hereunto subscribed my name this 8th day of February, 1898.

EDWARD WESTON.
